INVENTOR

Ernest G. Lowe

BY W. H. Deasy, ATTORNEY

UNITED STATES PATENT OFFICE.

ERNEST G. LOWE, OF HERTFORD, ILLINOIS.

HOLDFAST FOR STRETCHING HIDES AND LEATHER.

Application filed September 3, 1925. Serial No. 54,268.

My invention relates to hold-fasts or devices for holding hides and leather upon a board or frame while being dehydrated.

The primary object of my invention is to produce a hold-fast to be used in affixing hides and leather to a board or frame while being dehydrated that will be certain in operation, easy to attach and detach and that can be constructed at a low cost.

Another object of my invention is to provide a hold-fast which may be successfully used without leaving an imprint on either side of the leather or hide being dehydrated, and at the same time will be of great durability, the same hold-fast being used with hundreds of different hides.

Other and further objects and advantages of my invention will be clearly set forth in the description, claim and drawings, in

which:

Fig. 1 is a plan view showing the use of my invention.

Fig. 2 is a view of my invention as applied to a different type of frame.

Fig. 3 is a side elevation.

Fig. 4 is an end elevation.

Fig. 5 is a plan view.

In the process of manufacturing leather from hides, the hide becomes hydrated since the tan bark or other extracts used in tanning must be used in a liquid form, the major component of which is water. The porosity of the hide causes it to absorb a large portion of the liquid with which it is treated, resulting in material expansion of its superficial area.

In order that the hide or leather may not unduly contract when being dehydrated, it is customary to stretch it by various means, one of the most common of which is by tacking it upon wooden boards prepared for the purpose.

When the hide or leather is being treated, the process of dehydration causes the hide to contract with considerable force from all directions, so that if it is not securely tacked at all points along the marginal edge, the contraction withdraws the tacks and not only allows the hide to shrink to less area, but to shrink unevenly, so that it is not of a uniform thickness.

If any form of clamp is used to hold the marginal edges in place, the jaws of the clamp must be held together with sufficient force to prevent the hide from slipping out

of the jaws, and it has been found by experience that wherever the jaws have been clamped upon the hide or leather during the process of dehydration that particular part of the hide or leather retains the mark of the jaws of the clamp and materially deteriorates the leather, which must be trimmed away at a loss.

To avoid these objections and needless waste, it has been found that tacks or small pointed fasteners, capable of piercing the marginal edge of the hide, when placed sufficiently close together divide the tension of contraction among the various holders and the leather is but slightly damaged, and, in fact, in some cases the holes pierced through the marginal edges of the hide entirely disappear in the process of finishing the leather.

However, a serious objection to the use of tacks, in addition to the fact that they sometimes are withdrawn, and that they become scattered about the floor of the tannery, frequently piercing the soles of the shoes of the workers and causing injury thereby, is that they are withdrawn from the boards and still cling to the leather and they injure, and sometimes entirely destroy, the face of the embossing plates, which are quite expensive, or other machines through which it is necessary to pass the leather in the process of finishing.

Another disadvantage in the use of tacks is the fact that new tacks have to be constantly supplied to take the place of those bent, injured or lost in the usual course of operation.

To overcome the above objections and difficulties, I have devised a very simple, positively accurate hold-fast that can be instantly attached to the edge of the hide or leather without the use of any tools and can be quickly attached and detached from a suitable frame with no tools other than the human hand, and which will remain fixed both in the marginal edge of the hide or leather and in the board until removed by a conscious act of the operator.

Because my invention is preferably made by stamping it from sheet metal, it may be used over and over again for a period of years without serious wear or liability of becoming inoperative.

As shown in Fig. 3 my invention consists of a main body portion 1, substantially rec-

tilinear in outline, having its inner end 2 depressed at right angles to its major axis, thereby forming a shoulder 3, for the purpose of preventing the careless or indifferent operator from pricking the hide at too great a distance from its marginal edge. The depressed portion 4 serves the purpose of holding the pricker 5 from longitudinal movement since when in a closed position the pricker 5 enters the orifice 6 in the main body portion 1.

The opposite end of the main body portion 1 is provided with two ears 7, which project downwardly at right angles to the major axis of the body portion 1. The ears 7 are curvilinear in cross section and slightly tapered, at their lower ends, in order to facilitate their insertion in round perforations 8 in a suitable frame 9.

The ears 7 are, also, provided with a slight embossed portion 10, which when inserted through the perforations 8 prevents them from being accidentally dislodged therefrom.

The ears 7 are formed of spring or other resilient steel, so that at a slight pressure of the hand they are forced towards each other sufficiently to allow free insertion into the perforations 8 beyond the embossed portions 10.

Another rectilinear member 11 is superimposed upon the main body portion 1, being of equal length and width thereto and held firmly therewith by means of suitable rivets 12.

The member 11 being preferably stamped from sheet metal has ears 13 turned upwardly at right angles to its major axis to form bearings 14 about which revolves an eccentric 15, actuated by a lever handle 16. Parallel with the main body portion 1 and the member 11 and riveted thereto at one end is a flat spring 17, normally adapted to hold the pricker 5 at its maximum upward limit. The point of the cam 15 is exaggerated or extended at 18 adapting it to press the spring portion 17 flat down against the member 11, until the point of the pricker enters the orifice 6 in the main body portion 1.

It is obvious that when a hide is inserted in the open space, 20, between the main body portion 1 and the member 11, and the cam 15 is caused to be pressed down, the spring 17 by means of rotating the lever handle will cause the pricker 5 to be forced through the marginal edge of the hide or leather to which it is applied, and as the lever handle reaches the position shown in the dotted lines 21, the thumb and fore-finger of the hand automatically grasp the resilient ears 7, pressing them together as they are inserted into the perforations 8, or through

the meshes 22 of a screen frame, as shown in Fig. 1.

65

It is, also, apparent that when the lever handle 16 is thrown upward as shown in Fig. 3, the spring 17 will withdraw the pricker 5 from the hide or leather, thus instantly releasing it. It will be noted that when the pricker 5 is at its maximum limit the point is still within the orifice 19, thereby protecting the point against injury and at the same time preventing the point from injuring the hand of the operator. This construction further facilitates the releasing of the hide because the point is withdrawn entirely therefrom. The lever handle being held in place by a pintle 26 is provided with an extension 27 to facilitate the releasing of the hide by striking the extension 27 with a mallet or any other suitable tool.

75

It is sometimes found convenient, after the leather has become dehydrated to a point where it will no longer be materially affected by contraction and expansion, although not being ready for the finishing process, to suspend it by means of rope or chain, or otherwise, from tiers. Therefore, in order to meet this condition, I have provided a suitable hook 23 on one end of my device adapted to engage the link of a chain or to hold fast to a rope by means of a triangular opening 24, the weight of the hide 95 or side of leather suspended causing the rope to firmly enter the crotch 25 of the opening 24, thereby preventing movement in the direction of the major axis of the rope.

85

Having fully described my invention, its use and construction, what I claim as new and useful and desire to secure by Letters Patent is:

90

A hold-fast for securing and holding sides of leather and hides to a frame for dehydrating them, comprising a cam actuated pricker adapted to pierce the marginal edge of sides of leather and hides, a shoulder adapted to limit the distance from the edge of sides of leather and hides that said pricker can pierce the said hides and sides of leather, a cam for actuating said pricker, a spring for withdrawing said pricker, a lever arm for actuating said cam, a pintle about which said cam rotates, upwardly turned ears providing bearings for said pintle, a guard protecting the point of said pricker, a plurality of resilient ears adapted to engage apertures of like contour, said ears being circumferentially embossed to prevent their accidental withdrawal from said apertures, and a triangular hook adapted to grip and hold a rope or chain link.

100

In witness whereof I have hereunto affixed my signature this 29 day of Aug. 1925.

ERNEST G. LOWE.
